Primary Examiner — Ian Simmons*Assistant Examiner* — Rashida C McCoy(74) *Attorney, Agent, or Firm* — McDermott Will & Emery LLP(57) **CLAIM**

We claim the ornamental design for a plate, as shown and described.

DESCRIPTION

FIG. 1 is a first perspective view of a plate according to the present invention;

FIG. 2 is a second perspective view of the plate of FIG. 1;

FIG. 3 is a top plan view of the plate of FIG. 1;

FIG. 4 is a front elevation view of the lid of FIG. 1, the rear elevation view, and side elevation views being identical images thereof; and,

FIG. 5 is a bottom plan view of the lid of FIG. 1.

The broken lines form no part of the claimed design.
